(57) **CLAIM**

The ornamental design for a magazine file, as shown and described.

DESCRIPTION

FIG. 1 is a front perspective view of a magazine file; FIG. 2 is a front elevation view thereof; FIG. 3 is a rear elevation view thereof; FIG. 4 is a top view thereof; FIG. 5 is a bottom view thereof; FIG. 6 is a right side view thereof; and, FIG. 7 is a left side view thereof.

The broken lines are included to show portions of the magazine file that form no part of the claimed design.

The broken away symbols in the drawings indicate that the appearance of any portion of the article between the break lines forms no part of the claimed design.

The short and long dash broken lines represent boundaries of the claimed design and form no part of the claimed design.
